UNITED STATES PATENT OFFICE.

HOWARD A. WOLF, OF ELKINS PARK, PENNSYLVANIA, ASSIGNOR TO EDWIN WOLF, BENJAMIN WOLF, CLARENCE WOLF, LOUIS WOLF, AND ALBERT WOLF, ALL OF PHILADELPHIA, PENNSYLVANIA, COPARTNERS, TRADING AND DOING BUSINESS AS WOLF BROTHERS.

ENVELOPE.

Application filed January 2, 1924. Serial No. 683,900.

My invention relates to envelopes or paper bags and more particularly to that type which is provided with means, in the nature of a handle, enabling the envelope or bag to 5 be conveniently carried.

Heretofore envelopes and paper bags have been provided with carrying handles, but it has been found in practice that such envelopes or bags are not entirely satisfactory, 10 since when they are carried they tend, under the weight of their contents, to open, or if opening is prevented, they are more or less complicated in design, difficult to close and have reduced capacity.

Now it is the object of my invention to provide an envelope or paper bag which will be adapted to be carried by a handle which will not open when carried and at the same time one which will be extremely simple to 20 close and made ready for carrying.

Further objects of my invention are to provide an envelope or bag which will be readily blanked out without waste of stock and which will be efficient in service.

Having now indicated in a general way the nature, purpose and advantage of my invention, I will proceed to a detailed description thereof with reference to the accompanying drawings in which I have illustrated a preferred embodiment and in 30 which:

Figure 1, is a plan view from the rear of the upper portion of an envelope embodying my invention, the envelope being open.

Figure 2, is a view similar to that of Figure 1, the envelope being closed.

Figure 3, is a view similar to that of Figure 1, the envelope being secured in closed position.

Figure 4, is a sectional view on line 4—4, Figure 3.

Figure 5 is a plan view of the upper portion of the back of an envelope embodying a modification of my invention.

Figure 6 is a view of the rear of an envelope similar to that of Figure 5, partially closed.

Figure 7, is a view similar to that of Figure 5, with the envelope in fully closed position.

Figure 8, is a sectional view on line 8—8, Figure 7.

Figure 9, is a sectional view on line 9—9, Figure 7.

The envelope, as illustrated in Figures 55 1—4, and it will be understood that my invention is equally applicable to containers which would be called bags, is formed from a single blank folded to form a front wall *a* and a back wall *b*, the front and back being joined 60 together along the edges as is customary.

The front wall *a* is made longer than the back wall to form a closing flap *c* adapted to be folded over against the outside of the back wall *b* and form a closure for the open 65 end of the envelope.

The flap *c* is slit to form a handle *d* in such a manner as to leave on the flap adjacent to line of fold the opposite projections *e*, *e*. The handle is provided with angularly 70 extending slits *x*, *x*, and a slit *y*, extending horizontally between intermediate points on slits *x*, *x* to form a pair of tabs, *f*, *f*.

The back wall *b* of the envelope is provided with two spaced curved slits extending 75 downwardly from its upper edge forming the oppositely extending projections or ears, *g*, *g*. The front wall is provided with two vertical slits, *p*, *p*, positioned in relation to the slits forming the projections *g*, *g*, so as to be substantially chords of the curves thereof.

The operation of the embodiment of my invention shown in Figures 1—4 will, it is believed, be obvious from an inspection of the figures.

After the article or articles desired to be carried in the bag are placed therein, the flap *c*, is folded over against the outside of the back *b*, leaving the handle extending beyond the bag. The projections *e*, *e* on the 85

flap and the ears, *g*, *g* are then found to align and are drawn through the vertical slots in the front of the bag by drawing that portion of the bag and the flap outside of the slots at both sides of the bag forward while pushing in that portion of the bag and flap between the slots. The bag will then be locked closed, with the flap locked in its closed position.

10 When the bag is picked up, the fingers are thrust through the handle displacing tabs *f*, *f*, one up and one down. The upper tab forms a surface for the fingers, while the lower tab serves as a closure for that portion 15 of the open end of the bag below the handle and not closed by the flap *c*, as will be seen from an inspection of Figure 3.

Referring now to Figures 5-9 in which is illustrated a modification of my invention, 20 the front and back walls of an envelope are indicated by the letters *a'* and *b'* respectively.

The handle *c'* is joined integral with the front wall and slit angularly and horizontally to form the tabs *f'*, *f'*.

The front and back walls are extended upward beyond the base of the handle to form flaps *h*, *h*, adapted to be folded over against the back wall on a line with the base 30 of the handles to form a closure for the envelope. The edges of the flaps *h*, adjacent the handle extend toward each other beyond the outer edges of the handle and are cut at an angle, thus forming projecting portions 35 or ears, *i*, *i*.

The operation of the modification of Figures 5-9 will be obvious. When the bag is filled, the flaps *h*, *h*, are folded down against the back wall. That part of the flaps 40 formed in the wall opposite to that against which the flaps are folded will close the opening of the bag and the projection or ears *i*, *i* will engage behind the handle as shown in Figures 7 and 8, thus effectively locking the flaps in closed position. On 45 grasping the handle the tabs *f'*, *f'*, will be displaced and serve as a closure for the opening of the bag within the confines of the handle and as a surface for the fingers as described 50 in connection with Figures 1-4.

As a result of my invention there is produced a bag which may be effectively closed and kept closed and easily carried from place to place, at the same time there is produced a bag which may be easily and economically produced and readily made use of.

Having now fully described my invention, what I claim and desire to protect by Letters Patent is:

60 1. An envelope comprising front and back walls joined along three sides, a flap formed by an extension of one of said walls adapted to be folded down against the opposite wall and a handle formed in said flap 65 adapted to lie in the plane of the walls, said

handle being slit horizontally and angularly to form tabs adapted to be bent on parallel lines to form upwardly and downwardly extending tabs to provide a surface for the fingers and a closure for that part of the 70 envelope beneath the handle, respectively.

2. An envelope comprising front and back walls, a flap formed by an extension of one of said walls, a handle formed in said flap, one of said walls being slit downwardly adjacent to the edges of the handle, and oppositely extending projections formed in said flap and in one of said walls adapted when the envelope is closed to be extended through the slits in said other wall. 75

3. An envelope comprising front and back walls, a flap formed by an extension of one of said walls, a handle formed in said flap, oppositely extending projections formed in one of said walls, the opposite wall being 80 slitted adjacent to the base of said projections and oppositely extending projections formed in said flap and adapted to overlie said projections in one of said walls when the envelope is closed, said overlying projection being adapted to be extended 85 through said slitted wall to secure the envelope in closed position.

4. An envelope comprising front and back walls, a flap formed by an extension of said 90 front wall, a handle formed in said flap, oppositely extending arcuate projections formed in said flap adjacent to the base of the said handle, oppositely extending projections formed by arcuate slits in said back 95 wall adjacent to the upper edge thereof and downwardly extending slits in said front wall, said projections in said flap and said back wall being adapted to overlie when said envelope is closed and be extended through 100 said downwardly extending slits in said front wall to secure said envelope in closed position.

5. An envelope comprising front and back walls, a flap formed by an extension of the 110 front wall, a handle formed in said flap, tabs formed by angular and horizontal slits in the handle, oppositely extending projections formed in the flap, oppositely extending projections formed in the back wall and 115 downwardly extending slits in the front wall, said projections in the flap and back wall being adapted to overlie when the flap is in closed position and to be extended through said downwardly extending slits in the front wall to secure the flap and back wall to the front wall, said tabs formed in 120 said handle being adapted to be extended respectively upwardly and downwardly to provide a finger aperture in said handle and to respectively provide a bearing surface for the fingers when the bag is carried and a closure for that part of the mouth of the envelope beneath the handle. 125

6. An envelope comprising front and back 130

walls, a closure flap formed as an extension of one of said walls and arranged to be folded over the outer side of the other of said walls, a projection formed in the flap, 5 and a similar projection formed in the wall over which the flap is foldable and aligning with the first projection when the flap

is folded, the wall carrying the flap being slitted for the reception of both projections to form a closure for the envelope.

In testimony of which invention, I have hereunto set my hand, at Philadelphia, Pa. on this 27th day of December, 1923.

HOWARD A. WOLF.
